(57) **CLAIM**

The ornamental design for a holder, as shown and described.

DESCRIPTION

This application claims priority to co-pending U.S. patent application Ser. No. 29/837,781 filed May 9, 2022, the contents of which are incorporated herein by reference.

FIG. 1 is a perspective view showing a front end, a right side, and a top side of a holder in accordance with this invention.

FIG. 2 is a top plan view showing the top side of the holder of FIG. 1.

FIG. 3 is a bottom plan view showing a bottom side of the holder of FIG. 1.

FIG. 4 is a right elevational side view showing the right side of the holder of FIG. 1.

FIG. 5 is a left elevational side view showing a left side of the holder of FIG. 1.

FIG. 6 is a rear end elevational view showing a rear end of the holder of FIG. 1; and,

FIG. 7 is a front end elevational view showing the front end of the holder of FIG. 1.

In the drawings, the broken lines represent environmental structure forming no part of the claimed design.
